CLAIM

The ornamental design for product package, as shown and described.

DESCRIPTION

FIG. 1 is a perspective rear view of a product package showing our new design, with a view of the interior;

FIG. 2 is a top plan view thereof;

FIG. 3 is a rear view thereof;

FIG. 4 is a front view thereof; and,

FIG. 5 is a left side view thereof.

The broken lines shown are for illustrative purposes and form no part of the claimed design.
